UNITED STATES PATENT OFFICE.

CHARLES GANZ, OF NEW YORK, N. Y., ASSIGNOR TO TREIBACHER CHEMISCHE WERKE GESELLSCHAFT MIT BESCHRANKTER HAFTUNG, OF TREIBACH, AUSTRIA-HUNGARY, A CORPORATION OF AUSTRIA-HUNGARY.

LIGHTER.

1,088,271.

Specification of Letters Patent. Patented Feb. 24, 1914.

Application filed November 13, 1912. Serial No. 731,045.

To all whom it may concern:

Be it known that I, CHARLES GANZ, a citizen of the United States of America, residing in the borough of Manhattan, city, county, and State of New York, have invented certain new and useful Improvements in Lighters, of which the following is a specification, reference being had to the accompanying drawings.

10 This invention relates to improvements in lighters and particularly to improvements in lighters in which is used a spark-giving alloy, sometimes called pyrophoric metal; and an object of this invention is to provide a 15 lighter of this type which will be certain in its action.

Another object of this invention is to provide a lighter of this type which will be simple in construction, comparatively cheap in 20 manufacture and efficient and durable in operation and use and which will require practically no expense for upkeep or repairs.

In the drawings illustrating the principle of this invention and the best mode now 25 known to me of applying that principle, Figure 1 is a central vertical section through the lighter, the parts being shown in assembled relation; Fig. 2 is an elevation looking in the direction of the arrow A of Fig. 30 1; Fig. 3 is a horizontal section on the line B—B of Fig. 1; Fig. 4 is a perspective view showing one manner of use of the device; Fig. 5 is a detail illustrative of the carrier-pin; Fig. 6 is a detail in elevation of the 35 vapor-collecting guide-tube; Fig. 7 is a detail of the wad-holder; Fig. 8 is a detail in plan of the strip from which the wad is formed; Fig. 9 is a detail of the abrader-pin or spark-producer; Fig. 10 is a detail in 40 perspective of the alloy-receiver (or alloy-holder); Fig. 11 is a detail in perspective of the stick of alloy.

The body portion of the device is in the form of a small can or reservoir *a* the top of 45 which is closed by a cover-plate *b* having a centrally-disposed opening or mouth *c* the wall of which is formed by an inwardly-projecting rim-flange or annular lip *d* screw-threaded on its interior. On the outside of 50 this annular lip *d* is suitably mounted the upper end of a vapor-collecting tube *e* the inner or lower end of which is formed with holes *f* designed to allow the vapor to pass from the absorbent material, such as cotton

g, contained in the can *a* and surrounding the tube *e*, as shown in Fig. 1. This absorbent material is maintained saturated with a suitable hydrocarbon oil, preferably high-grade benzin, gasoline or naphtha. The outer end of the carrier-pin *h* is in the form of a head *i* which serves as a finger-hold (Fig. 4) and which is formed with an annular flange *i'* just below which are screw-threads *j* adapted to engage the screw-threads *k* formed on the interior of the annular wall *d* of the mouth or opening *c*. By two-thirds of a turn of the carrier-pin *h*, engagement is made between the same and the annular wall *d* of the mouth *c* of the can, thereby tightly closing the latter and preventing the escape of the vapor, as well as locking the carrier-pin *h* securely in place. The body portion or shank *m* of the carrier-pin *h* is conical in form to facilitate its ready insertion in the can *a*; and the inner or torch end of the carrier pin is formed with a socket *n* into which is driven the butt-end of the abrader-pin *o*. Just above its lower end or torch-end the carrier-pin *h* is exteriorly threaded at *p* and is thereby adapted to engage with the threaded end of the wad-holder *q*, which is formed with prongs or claws *r* adapted to hold securely the wad *s*. This wad is made out of suitable material, such as asbestos, and is preferably rolled from a strip *t*, which is shown in detail in Fig. 8. This strip is slotted in order to make it more absorbent; and, when the strip is rolled and pressed into the form of a wad, its central opening *u* is somewhat larger in diameter than the diameter of the abrader-pin *o*. To one side of the can *a* is suitably fastened an alloy-holder *v* which is in the form of a channel adapted to receive the stick of spark-giving alloy *w* shown in Fig. 11.

The wad-holder *q* and the wad *s* held by the same constitute in reality a sort of torch, which is substantially frusto-conical in shape. This shape has the advantage, among others, that the oil-soaked wad is not rubbed over the alloy when the carrier-pin is tilted, as shown in Fig. 1, to bring the scraping edge of the spark-producer into proper position for tearing the alloy, and misfires are thereby reduced to a minimum. It is intended that the wad *s* shall be kept undisturbed in the grip of the claws *r*, until

it is worn out and becomes useless, whereupon the claws are opened, a new wad is substituted for the one worn-out and the claws again are bent firmly into gripping position.

An important feature of this invention resides in the working-end of the abrader *o*. It is to be noted that this end is integral with the body of the abrader and is provided with an edge *o'*, which in Fig. 9 is shown as being formed by undercutting the end of the abrader so that it is substantially frusto-conical in form. In this way the working-end of the abrader *o* is given a sharp edge, which does not readily become dull by use. It is to be noted that since the tip end or working end of the abrader is integral with the body portion thereof, no fastening devices are needed to fasten the tip end to the body of the abrader; and from this it results that the working tip end of the abrader or spark-producing element is free from obstructions to its effective operation. The abrader is preferably of hardened heat-resisting metal and is durable, retaining its sharp edge. The substantially frusto-conical shape of the abrader-head *o''* affords sufficient body to prevent breaking away or chipping off in use.

The smaller end of the wad-holder *q* is opposed to the smaller end of the spark-producer *o* and the torch formed by the wad *s* and its holder *q* extends laterally beyond the base or larger end of the spark-producer so that the torch intercepts the sparks and certainty of ignition is insured.

The receptacle part or body *a'* of the can or box *a* is drawn into shape and is, therefore, a single piece of metal without seams, crevices or slots and is thus made vapor-tight so that the vapor of the hydrocarbon oil with which the cotton *g* is saturated will be retained and the device may be used for a long time without the necessity of replenishing the supply of hydrocarbon.

There are at the top of the carrier-pin *h* a plurality of screw-threads *j* each of which is independent of the others and (in the particular example given) makes two-thirds of a turn, so arranged that it requires only two-thirds of a turn to fasten the carrier-pin in place or to release the same. Obviously, if there were two threads each of one-half turn, only a half turn of the carrier-pin *h* might be necessary in order to engage or release it from the box. This is an important feature of this invention, since it makes the device handy, convenient and rapid in use. The screw-threads *k* serve also to seal the mouth or opening *c*, when the carrier-pin is screwed into place.

It will be understood that the centrally-

disposed tube *e* serves as a receiver and guide-tube for the carrier-pin *h*, and keeps free an opening for the same in the mass of absorbent material with which the inside of the can *a* is stuffed.

In Fig. 4 there is illustrated one manner of use of the device. By giving the carrier-pin *h* a part (two-thirds) of a turn, it will be loosened from the can *a* and may then be wiped lengthwise over the exposed face of the alloy *w*, the abrader *o* being held in a slanting position so as to bring the edge *o'* thereof into tearing or scraping relation with the alloy. The sparks given off by the alloy will ignite the vapor of the hydrocarbon with which the absorbent wad *s* is saturated, whereupon a luminous torch-like flame is produced; indeed the carrier-pin *h* may be used after the manner of a torch, since the flame will persist for some time, depending in part upon the degree of saturation of the wad *s*.

I claim:

1. In an igniter, a carrier-pin provided with a spark-producing element the working tip end of which is integral with the element and free from obstructions to its effective operation and is recessed to form a frustum-shaped abrader the larger base of which has a scraping edge.

2. In an igniter, a carrier-pin having a sparking element the head of which is recessed and is thereby formed with a tearing or scraping edge; a wad of absorbent material which is formed with an opening through which said sparking element extends and which extends laterally beyond the head of the latter and is thereby adapted to intercept the sparks produced by the scraping edge thereof; and wad-holding means.

3. In an igniter, a carrier-pin having a sparking element the head of which is substantially frusto-conical and is formed at its outer end with a tearing or scraping edge; a wad of absorbent material which is formed with an opening through which said sparking element extends and which extends laterally beyond the head of the latter and is thereby adapted to intercept the sparks produced by the scraping edge thereof; and a substantially frusto-conical wad-holder; the smaller ends of said wad-holder and sparking element being opposed.

Signed at the borough of Manhattan, city, county and State of New York, this eleventh day of November, A. D. 1912, in the presence of the two undersigned witnesses.

CHARLES GANZ.
